UNITED STATES PATENT OFFICE.

MATTIE ANDRES, OF ST. LOUIS, MISSOURI.

PISTON-PUMP.

1,112,187.

Specification of Letters Patent. Patented Sept. 29, 1914.

Application filed August 29, 1912. Serial No. 717,654.

To all whom it may concern:

Be it known that I, MATTIE ANDRES, a citizen of the United States, residing in the city of St. Louis and State of Missouri, have 5 invented certain new and useful Improvements in Piston-Pumps, of which the following is a specification.

This invention relates to multi-cylinder piston pumps, and contemplates, generally, 10 the provision of an improved pump of that character designed primarily for supplying a current of air for gas generators and other devices requiring same.

The features of novelty relate to and reside in the construction of the pump and in the connections between the drive shaft or shafts and the pistons so that a continuous non-pulsating current of air will be forced through the outlet pipe, and, more particularly, 20 in the use of flexible diaphragms or partitions in connection with the pistons, in order to produce an air current having a constant and substantially uniform pressure.

In the accompanying drawings forming 25 part of this specification, in which like numbers of reference denote like parts wherever they occur, Figure 1 is an end elevation of a multi-cylinder piston pump embodying the present invention; Fig. 2 is a top plan 30 view of same; Fig. 3 is a side elevation of same; Fig. 4 is a sectional view, on an enlarged scale, on the line 4—4, Fig. 3; and Fig. 5 is a similar sectional view showing an alternate form of cylinder.

The pump illustrated in the drawings is 35 of the double-acting type and consists of a plurality of barrels or cylinders 1 wherein the pistons 2 reciprocate, and an operating shaft 3 or a plurality of such shafts with 40 which said pistons are connected, as herein-after described. Each shaft 3 is journaled in suitable journal-boxes 4, which are secured to standards 5 by any suitable means, and has a gear 6 rigidly mounted thereon, 45 each gear 6 meshing with and being driven by a gear 7 rigidly mounted on drive shaft 8, which is journaled in suitable journal-boxes 9 secured to standards 5. A rope 10 is wound on a drum 11 that is loosely mounted 50 on drive shaft 8, and passes over a sheave

12 fastened to a ceiling 13 or other support. Said rope 10 passes over a pair of pulleys 14, one of said pulleys being secured to said ceiling and the other being attached to a weight 15, which holds said rope in tension 55 and causes drum 11 to rotate in one direction. A pawl 16 is pivoted at 17 to gear 7 and is held in engagement with a ratchet 18 by means of a spring 19, said ratchet being secured to drum 11 so as to rotate therewith. 60 By this arrangement, when the pull of rope 10 causes drum 11 to rotate, ratchet 18 rotates with said drum and thereby causes gear 7 to rotate through the medium of pawl 16, with the result that said gear 7, in turn, rotates gears 6 and shafts 3. A bracket 20 is secured to one of the standards 5 and is arranged to form a bearing for drum 11. The outer end of drum 11 projects from said bracket, in order to allow a crank handle 70 (not shown) to be attached thereto for the purpose of rotating same in the reverse direction, whenever it is necessary to rewind rope 10 on drum 11 after weight 15 pulls said rope to such extent that same is nearly 75 unwound from said drum.

The barrels may be arranged in a group or set or a plurality of groups or sets of any number of barrels to each group or set, but for the purpose of illustration the barrels 1 80 of the pump depicted in the drawings are arranged in two groups or sets, each of which comprises three barrels 1, which may be suspended from a member 21 bolted or otherwise secured to standards 5, as herein-after described, or may be supported in any other suitable manner. Each barrel 1 is preferably disposed substantially vertical, and comprises upper and lower halves 22, said halves being preferably formed sym- 85 metrically so as to be interchangeable and having annular flanges 23 on their adjoining edges, which flanges are secured together by bolts 24 or other suitable means. Each half 22 of barrel 1 is hollow and is prefer- 90 ably formed with the configuration of a frustum of a cone, its smaller end being closed and its larger end being open and bearing an annular flange 23, so that, when 95 two halves 22 are bolted together to form a 100

barrel 1, as hereinabove described, said barrel will be larger through its middle than at its ends. The closed end of each half 22 has a central opening 25, which is preferably 5 screw-threaded, the opening 25 in the upper half 22 receiving a screw-threaded boss 26, borne by the lower side of a member 21, and the opening 25 in the lower half 22 being closed by a screw-threaded plug or cap 27. 10 The boss 26 supports the barrel 1 and contains an opening which extends through the member 21 and, also, through another screw-threaded boss 28 on the upper side of said member, in order to allow the piston-rod 29 to extend therethrough and, also, to afford 15 a guide for said piston-rod. A cap 30 on boss 28 contains an opening through which piston-rod 29 extends, and holds packing 31 around said piston-rod, in order to prevent 20 leakage of the air from said barrel.

A boss 32 borne by the closed end of each half 22 contains a screw-threaded opening in which a bushing 33 is screwed. The inner end of bushing 33 has an inwardly projecting annular flange 34, which forms the walls of an opening 35, said opening communicating with the interior of half 22 and said flange 34 forming the seat for an inlet valve 36 located on one side thereof; and, 25 also, a stop for a member 37 located on the other side thereof, which member fits in the bushing 33. Said member 37 contains an opening through which the stem 38 borne by valve 36 is adapted to slide and, also, 30 an orifice 39 or a plurality of such orifices to permit the ingress of air into the barrel 1, when the valve 36 is unseated. Said valve 36 is adapted to open inwardly by the suction stroke of piston 2 and is normally 35 held in engagement with its seat 34 by a spring 40, which is preferably coiled around the valve-stem 38 so as to press against member 37 and, also, against a nut 41 borne by said stem. The casing 42 of an outlet valve 45 is secured to a boss 44 borne by the closed end of half 22, said boss 44 having an opening 45, which communicates with the interior of said half and, also, with the interior of said valve-casing, in order to permit the egress 50 of air from the barrel 1, when said valve 43 is unseated. Said outlet valve 43 may be a check valve of any ordinary construction, an angle check valve being depicted in the drawings for the purpose of illustration. A 55 partition 46 in casing 42 contains an opening 47 to permit the egress of air therethrough and forms a seat for the valve 43, which is hinged at 48 and is normally held in engagement with said seat by means of a 60 spring 49. An opening 50 in casing 42 affords access to the interior of said casing and is closed by a removable plug or cap 51.

The casing 42 of the outlet valves 43 at the upper ends of each barrel 1 of one group

are communicatively connected to a pipe 52, 65 and the casings 42 of the outlet valves 43 at the upper ends of each barrel 1 of the other group are, in like manner, connected to another pipe 52, the casings 42 of the outlet valves 43 at the lower ends of each barrel 1 70 of both groups being connected to a pipe 53. Both of the pipes 52 and pipe 53 are connected to an outlet or discharge pipe 54 by means of a four-way T 55 or other suitable connection, said outlet pipe leading to 75 a carbureter or other apparatus (not shown).

Each piston 2 consists of two disk-shaped members 56 which are connected by bolts 57 or other suitable means. The reduced end 80 58 of piston-rod 29 extends through a central opening in each member 56 and bears a nut 59, which holds said members on said reduced end. A flexible diaphragm or partition 60 of leather, rubber, or any other 85 suitable non-porous fabric has its peripheral edge secured between the flanges 23 of halves 22 and its middle part secured between the members 56 of piston 2, and thereby separates the interior of barrel 1 into two non- 90 communicating compartments. The diaphragm 60 works with piston 2 in barrel 1, and, in order to prevent the edges of members 56 from cutting said diaphragm, each member 56 has its peripheral edge formed 95 into a flange 61, the flange 61 on the upper member 56 being turned upwardly and the flange 61 on the lower member 56 being turned downwardly. During each upward stroke of piston 2, the upper outlet valve 43 100 opens automatically and thereby allows the air in the upper part of the barrel 1 to discharge through the pipe 52 into the outlet pipe 54, and the lower inlet valve 36, also, opens automatically and thereby permits the 105 ingress of air into the lower part of said barrel; and during each downward stroke of piston 2, the lower outlet valve 43 opens automatically and thereby allows the air in the lower part of barrel 1 to discharge through pipe 53 into the outlet pipe 54, and the upper inlet valve 36, also, opens automatically and thereby permits the ingress of air into the upper part of said barrel. It will be seen, therefore, that each stroke of piston 110 2 exercises both a suction and a discharge influence, *i. e.*, a suction and a discharge stroke, air being drawn into one end of barrel 1 at the same time that the air in the other end of said barrel is being expelled 115 therefrom. As the result, it will be apparent that during each stroke of each piston there is a discharge of air into the outlet pipe 54. By reason of using the flexible diaphragm 60 in connection with piston 2, an 120 air current having a constant and substantially uniform pressure can be obtained by 125 a relatively slow movement of said piston.

The several pistons 2 are individually connected with the operating shafts 3, as hereinabove stated, the pistons of one group of barrels being connected with one of said shafts and the pistons of the other group of barrels being connected with the other of said shafts, and each of said shafts being provided with a separate crank 62 for each piston of its particular group of barrels.

10 The upper end of each piston-rod 29 is preferably screw-threaded and has a member 63 secured thereto, said member being pivotally attached in a fork 64 formed on the lower end of a pitman 65, a pin 66 being passed through registering apertures in the fork prongs and said member, and the upper end of said pitman being attached in any usual manner to a crank 62 of a shaft 3. The cranks 62 of each shaft 3 are predeterminedly and accurately spaced apart in angular relation about said shaft, so that the beginning of the stroke of each piston will overlap the end of the stroke of a piston in advance thereof, with the result that there will be no interval between successive strokes.

The pull of weight 15 on rope 10 causes the operating shafts 3 to rotate relatively slow through the medium of drum 11 and gears 7 and 6 and thereby cause the pistons 2 to reciprocate and work the diaphragms 60 in the barrels 1, with the result that a continuous non-pulsating current of air having a constant and substantially uniform pressure will be forced through the outlet pipe 54. Inasmuch as the consumption of the air fluctuates, the speed at which the shafts 3 rotate varies with the rate at which the air is consumed and thereby maintains a constant and substantially uniform pressure of the air current.

In the alternate form of barrel 1 depicted in Fig. 5, same is designed for use in a single-acting pump. The upper half 22 is omitted entirely and a hollow member 67 having the same shape is substituted in lieu thereof, said member having an annular flange 68, which is connected to the flange 23 of the lower half 22 by means of bolts 24, and the peripheral edge of the diaphragm 60 being secured between said flanges 68 and 23. The upper inlet and outlet valves 36 and 43 are both omitted, and the closed end of said member contains a central screw-threaded opening 69 in which a lower boss 26 borne by member 21 fits, in order to support said barrel 1, the upper boss 28 being, also, omitted. An opening 70 in the closed end of member 67 permits the air to pass into and out of the upper part of barrel 1, when the piston 2 reciprocates in said barrel. In this form, the upward stroke of piston 2 opens the inlet valve 36 and thereby draws air into the

lower part of the barrel 1, and the downward stroke of said piston opens the outlet valve 43 and thereby allows the air in the lower part of said barrel to be expelled through the outlet pipe 54. The piston 2 is somewhat modified, the upper member 70 56 being omitted and an inverted bell-shaped member 71 being substituted therefor. The lower end of piston-rod 29 fits in an opening 72 in boss 73 borne by member 71 and is secured in said opening by a pin 74 or other suitable means. The lower member 56 is connected to member 71 by bolts 57, and holds the middle part of the diaphragm 60 between same and said member 71. By reason of using an inverted bell-shaped member 71, the circumferential wall of same prevents the diaphragm from being cut, when the piston reciprocates in the barrel 1.

It should be understood that, while a continuous non-pulsating current of air having a constant and substantially uniform pressure can be obtained from the use of barrels having flexible partitions actuated by their pistons, yet, the same result can be obtained if ordinary pistons and cylinders are used and arranged in the manner hereinabove described.

The operation of the pump is believed to be apparent from the foregoing, and, hence, to require no further or separate description.

I claim:

1. In a pump, the combination of a barrel having an opening in an end thereof, a flexible partition in said barrel, a reciprocatory piston working in said barrel and connected to said partition for actuating same, and a support having a pair of lugs located on opposite sides thereof, one of said lugs fitting in the opening in said barrel for supporting the latter, there being an opening extending through said lugs and said member for guiding the piston-rod.

2. In a pump, the combination of a barrel having an opening in an end thereof, a flexible partition in said barrel, a reciprocatory piston working in said barrel and connected to said partition for actuating same, a support having a pair of lugs located on opposite sides thereof, one of said lugs fitting in the opening in said barrel for supporting the latter, there being an opening extending through said lugs and said member for guiding the piston-rod, and a packing-retaining cap borne by the other of said lugs and having an opening for the piston-rod.

3. In combination with end standards, a pair of spaced horizontal members secured at their ends to said standards, said members having apertures therethrough, barrels disposed on the under sides of said members

and having bosses on their upper ends, means projecting down from the under sides of said members to engage said bosses to support the barrels from said members, piston-
5 rods extending through said apertures in said members and into the barrels, pistons in the barrels connected to the piston-
rods, means above said members for op-

erating the piston-rods, and means to connect the lower ends of the barrels together. 10

In testimony whereof I hereunto affix my signature in the presence of two witnesses.

MATTIE ANDRES.
